UNITED STATES PATENT OFFICE.

ALMON E. NORRIS, OF BROOKLINE, MASSACHUSETTS.

GRAB.

Application filed September 9, 1921. Serial No. 499,395.

This invention relates to grabs and is more especially, though not exclusively, concerned with single rope clam-shell buckets. The invention will be best understood by reference to the following description when taken in connection with the accompanying drawings of one specific embodiment thereof, while its scope will be more particularly pointed out in the appended claims.

10 In the drawings:

Fig. 1 is an end elevation of a grab exemplifying the invention, showing the same in its closed position;

15 Fig. 2 is an end elevation of the grab showing the same in its open position;

Fig. 3 is a side elevation of the grab as viewed from the right-hand side of Fig. 1;

20 Fig. 4 is a vertical sectional view on line 4-4 of Fig. 1;

Fig. 5 is a vertical sectional view on an enlarged scale of a mechanism for locking the grab in its closed position, this view showing the mechanism in its locked position;

25 Fig. 6 is a sectional view similar to Fig. 5, but showing the latch lever retracted in a horizontal direction to permit a locking means to lock without swinging movement of the latch lever;

30 Fig. 7 is a sectional view similar to Fig. 5, but showing the locking mechanism unlocked by the operation of its toggle and the swinging of the latch lever;

35 Fig. 8 is a sectional view on line 8-8 of Fig. 5;

Fig. 9 is a sectional view on line 9-9 of Fig. 5; and

40 Fig. 10 is a perspective view of the scoops and the frame detached one from the other.

Referring to the drawings, and to the embodiment of the invention which is selected for exemplification and having particular reference to Fig. 1, there is shown a grab having a pair of scoops 10 and 10' provided with jaws 12 and 12', the latter being suitably secured as by rivets 14 and 14' to end plates 16 and 16'. The plates at one end are united to those at the other end by curved plates 18 and 18' in any usual manner.

45 Referring now to Fig. 10, the scoops 10 and 10' are provided respectively with frames designated generally by the numerals 20 and 20', herein comprising pairs of hinges 22 and 22', and connecting portions 24 and 24' which, in the present example,

for convenience of manufacture are formed separately, and are suitably secured to the hinge pieces as by sets of flush rivets 26 and 26'. Each frame presents a generally U-shaped support for the upper margin of its scoop on its sides as well as its ends. The frames are suitably secured to their respective scoops as by fastening elements received in perforations therein. In the present example, the end plates and jaws are provided with sets of perforations 28 and 28', registering with corresponding perforations 30 and 30' provided in the hinge pieces 22 and 22', and receiving bolts 32 and 32', while the plates 18 and 18' are provided with perforations 34 and 34', registering with corresponding perforations 36 and 36' in the connecting portions 24 and 24', respectively, and receiving bolts 34 and 34'. If at any time the scoops should become damaged and require replacement, this can be accomplished without dismounting any parts of the operating mechanism by simply removing the bolts, 50 detaching the scoops and replacing them by new ones. This can be done very easily in the field and without the necessity of sending the grab to the maker.

55 In the present example, the hinge pieces of one scoop are pivoted by being connected to those of the other scoop by a hinge pin 40, best shown in Fig. 4, appropriately held in place therein as by nuts 42 threaded onto the ends thereof, and conveniently held against accidental turning movement by bolts 44 which extend through the nuts and through the hinge pin. The latter is preferably held against turning movement in one pair of hinges, herein the hinges 22', as by bolts 46 which extend through the hinge pin as well as through the bosses of the hinges, while on the other hand the hinge pin turns in the bosses of the other hinges 22.

60 The hinges are preferably provided with suitable means for limiting the opening movement of the scoops, herein lugs 48 and 48', herein formed integrally therewith and chambered to receive appropriate cushioning means such as wooden blocks 50 and 50', whose end grain is presented to the impact.

65 Referring now to Fig. 1, the frames 20 and 20' are supported by suitable supporting means, herein pairs of links 52 and 52', to which they are pivotally connected as by pivot pins 54 and 54', received in pairs of

ears 56 and 56' preferably formed as integral parts of the reinforcing bars or stiffeners 24 and 24', respectively, as best shown in Fig. 10. The members of each pair of links converge toward their upper ends (see Figs. 3 and 4), where they are pivoted together by a pin 58, best shown in Fig. 1. The links 52' constitute a frame, and they are rigidly secured to each other, as by tie-bolts 60 and 62, while the links are suitably spaced apart by several spacers, including spacers 64 and 66 (see Fig. 3).

In the absence of any means to hold the grab closed, the jaws will gravitate to an open position represented in Fig. 2, their opening movement being limited by the stops hereinbefore described. The closing movement of the grab is accomplished by a suitable cable, herein a rope 68, a series of sheave wheels 70, 72 and 74, and a closing lever 76. In the present embodiment, the sheave wheels 70 and 74 are mounted to turn on shafts 78 and 80 carried by the link 52', and the sheave wheels 72 on a shaft herein-after described carried by the closing lever 76. The grab is carried in a bight or loop of the cable passing over the sheave wheel 74, and leading thence first to a pair of the sheave wheels 72, and then to a pair of the sheave wheels 70. After passing over the latter, the two leads of the cable extend in an upward direction, and are secured to a suitable eye 82.

Referring now to the closing lever 76, the latter is herein pivoted to the scoop 10', as by a pin 84, best shown in Fig. 4, which extends through the lever as well as through ears 86 between which the lever is received. These ears are preferably formed as integral parts of the connecting portions 24' of the frame.

The grab is normally locked in its closed position by locking mechanism now to be described, reference being had at first to Fig. 4. Surrounding the hinge pin 40 is a sleeve 88, which may be secured thereto as by bolts 90, said sleeve being provided with ears 92 to receive a pin 94. Referring now to Fig. 5, this pin is normally locked to the closing lever by being received between what may be likened to a pair of relatively movable jaws or clamps 96 and 98, one being herein formed as an integral part of the closing lever 76, and the other as a part of a latch, herein a lever 100. This latch lever is herein mounted on a floating fulcrum 102, carried by a link 104, and which in turn is hung on a pivot 106 on the closing lever. The latch lever therefore has capacity for rocking movement on its fulcrum as well as movement in a generally horizontal direction, accompanying swinging movement of the link 104. Movement toward the left may be limited by engagement of the link 104 with the pin 94, as will be evident from

an inspection of Fig. 5, while movement toward the right may be limited by the provision of suitable means, herein stops 107 carried by the latch lever 100, and adapted to engage the lower edge of the closing lever, as shown in Fig. 6. Assuming the latch lever to be held against swinging movement on its fulcrum, introduction of the pin 94 between the jaws 96 and 98 is possible by crowding the latter away from the former, since the latch lever will recede in horizontal direction toward the right, to the position shown in Fig. 6. As soon as the pin 94 is in place, the latch lever will advance to its normal position, where it will be locked against movement about its fulcrum by suitable locking means, preferably that now to be described.

The latch lever 100 is further connected to the closing lever 76 by a toggle comprising two links 108 and 110, pivoted respectively to said levers by pivotal pins 112 and 114, and pivoted to each other by a pin 116. The axes of these pivots are normally substantially in line, and hence the latch lever is locked against swinging movement which would otherwise allow the pin 94 to be released from between the jaws 96 and 98. When, however, the intermediate pivot 116 is moved toward the right, to the position shown in Fig. 7, the pivot 112 is caused to approach the pivot 114 and to swing to the right-hand end of the latch lever in an upward direction, and the left-hand end in a downward direction, thus releasing the pin 94 and allowing the grab to open. The operation of the toggle may be accomplished in either of two ways, now to be described.

One of these ways is by the provision of an arm 118, preferably formed as an integral part of the link 108, and provided with suitable means, herein an eye 120, for the attachment of an operating rope 122, which extends therefrom first in a downward direction to and over a sheave wheel 124 rotatably mounted between the ears 126, best shown in Fig. 10, conveniently formed as integral parts of the connecting portions 24', said rope leading thence in an upward direction to and over a sheave wheel 128 rotatably mounted in a bracket 130, the latter being mounted on a pivot presented by the bolt 62 on the closing lever 76. The free end of the operating rope may be led to a convenient point, and when pulled, will operate the toggle to unlock the grab and allow the latter to open. When the rope is released, the toggle straightens to its normal position, its movement being adjustably limited by cooperating stops, one being herein a lug 134 conveniently formed integrally with the link 110, and the other being a set screw 136 having screw-threaded engagement with the arm 118 and adapted to contact with said lug. On the other hand, movement of the

toggle in the opposite direction is limited by suitable cooperating stops, herein a lug 138 conveniently formed as an integral part of the link 104 and adapted to strike a 5 shoulder 140 formed on the latch lever 100, as shown in Fig. 7.

A second way of operating the toggle will now be described, reference being had to Figs. 5 and 7. A weight 142 is suitably connected to the toggle as by forming the same 10 on the link 110 on the side of the latter which is opposite to the stops 134 and 136. Herein the lower part of the weight is received between the two sides of the latch 15 lever 100, which is bifurcated, as will be evident from an inspection of Fig. 8. Assuming the parts to be in the relative positions shown in Fig. 5 and the bucket descending, if the descent of the bucket is 20 abruptly stopped, the inertia of the weight 142 will cause the latter to continue in a downward direction, thus rocking the link 110 about its fulcrum 114 and causing the toggle to lift the right-hand end of the latch 25 lever and lower the left-hand end, as represented in Fig. 7. This opens the jaws 96 and 98, and allows the pin 94 to be released therefrom, whereupon the bucket opens to the position represented in Fig. 2. The open 30 bucket lands on the pile of material and immediately the closing lever 76 becomes locked to the pin 94, because when the lever descends upon the latter, the latch lever is engaged by the pin and caused to recede to 35 ward the right, as shown in Fig. 6, whereupon the pin enters between the jaws 96 and 98. The latch lever now advances to the position shown in Fig. 5, and the jaw 98 40 cooperating with the jaw 96 grips the pin 94 and locks the bucket in its closed position until it is again purposely unlocked.

Preferably suitable provision is made to 45 check the speed of opening movement of the bucket, thereby to prevent it from opening with too great a shock. The mechanism for accomplishing this will now be described, reference being had to Figs. 1 and 2. In the present example, I employ a cam 144 and a 50 cooperating roller 146, one carried by the supporting frame and the other by the closing lever. Herein there are two identical cams 144 formed as integral parts of the links 52', and there are two rollers 146 conveniently mounted to turn on a pin 148 55 which is the shaft on which the sheave wheels 72 are mounted to turn. The exact shape of the cam will depend upon the requirements of the situation, but usually it presents a more or less abrupt shoulder 150, 60 which resists travel of the roller in a downward direction toward the right, as viewed in Fig. 1,—that is to say, when the closing lever is released by the described locking mechanism and tends to carry the pivot 84 65 in a downward direction about the axis of

the pivot 54', thereby to open the bucket, the shoulder enforces a swinging movement of the upper end of the closing lever toward the left, thereby affording sufficient resistance to downward movement of the lever 70 toward the right to prevent the bucket from opening with too great a degree of force. The general operation of the bucket should be evident without further description.

Having thus described one embodiment of 75 the invention, but without limiting myself thereto, what I claim and desire by Letters Patent to secure is:

1. In a grab, the combination of a pair of pivoted scoops, supporting means on which 80 said scoops are pivotally supported and tend to gravitate to an open position, means for locking said scoops in their closed position, and a weight operated by an abrupt stop in the descent of the grab for causing said 85 scoops to be unlocked.

2. In a grab, the combination of a pair of pivoted scoops, supporting means on which 90 said scoops are pivotally supported and tend to gravitate to an open position, and means for locking said scoops in their closed position, said means including a latch and a toggle for locking said latch in its 95 scoop locking position.

3. In a grab, the combination of a pair of pivoted scoops, supporting means on which 100 said scoops are pivotally supported and tend to gravitate to an open position, means for locking said scoops in their closed position, said means including a floating latch lever 105 mounted for lengthwise movement, and means for normally locking said latch lever against swinging movement to an unlocking position while still permitting lengthwise movement thereof to cause said locking means to lock without swinging movement of said latch lever.

4. In a grab, the combination of a pair of pivoted scoops, supporting means on which 110 said scoops are pivotally supported and tend to gravitate to an open position, means for locking said scoops in their closed position, said means including a latch lever, a link on which said latch lever is fulcrumed and mounted to move lengthwise of said lever, and means for normally locking said latch lever against swinging movement to an 115 unlocking position while permitting said link to swing and said lever to be moved lengthwise to cause said locking means to lock without swinging movement of said latch lever.

5. In a grab, the combination of a pair of pivoted scoops, supporting means on which 120 said scoops are pivotally supported and tend to gravitate to an open position, means for locking said scoops in their closed position, said means including a latch lever, a link on which said latch lever is fulcrumed and mounted to move lengthwise, and a 125 130

toggle for normally locking said latch lever against swinging movement to an unlocking position while permitting said link and toggle to swing and said lever to be moved 5 lengthwise to cause said locking means to lock without swinging movement of said latch lever.

6. In a grab, the combination of a pair of pivoted scoops, supporting means on 10 which said scoops are pivotally supported and tend to gravitate to an open position, means for locking said scoops in their closed position, said means including a latch lever, a link on which said latch lever is fulcrumed 15 and mounted to move lengthwise, and a toggle for normally locking said latch lever against swinging movement to an unlocking position while permitting said link and toggle to swing and said lever to be moved 20 lengthwise to cause said locking means to lock without swinging movement of said latch lever, and means connected to said toggle to cause the same to unlock said scoops upon a predetermined bodily movement of 25 the grab.

7. In a grab, the combination of a pair of scoops, supporting means on which said scoops are pivoted and tend to gravitate to an open position, means including a closing 30 lever for closing said scoops, and means including a cam and a follower, one carried by said lever and the other by said supporting means independently of said scoops, to control the opening movement of said scoops.

8. In a grab, the combination of a pair of pivoted scoops, supporting means including a pair of links to which said scoops are pivoted, respectively, and on which said scoops tend to gravitate toward an open 40 position, closing means including a closing lever pivoted to one of said scoops at a point eccentric to the pivotal connection between such scoop and the link to which it is pivoted, and locking means including a pair of jaws and a part receivable therebetween to lock said lever to the jaw to which it is pivoted.

9. In a grab, the combination of a pair of pivoted scoops, supporting means including a pair of links to which said scoops are pivoted, respectively, and on which said scoops tend to gravitate toward an open position, closing means including a closing 50 lever pivoted to one of said scoops at a point intermediate the pivotal connections between said scoops and said links, and

locking means including a pair of jaws and a part receivable therebetween to lock said lever to the jaw to which it is pivoted.

10. In a grab, the combination of a pair 60 of scoops, scoop supporting means, grab closing means including a lever mounted to swing relatively to said supporting means, and cooperating means carried by said supporting means and by said lever to check the opening movement of said scoops.

11. In a grab, the combination of a pair 70 of scoops, scoop supporting means, grab closing means including a lever mounted to swing relatively to said supporting means, and means including a cam and a follower, one carried by said supporting means and the other by said lever to check the opening movement of said scoops.

12. In a grab, the combination of a pair 75 of scoops, scoop supporting means, grab closing means including a lever pivoted to one of said scoops to swing relatively to such scoop, and means including a cam and a follower cooperating therewith to check 80 swinging movement of said lever relatively to such scoop.

13. In a grab, the combination of a pair 85 of scoops, scoop supporting means, grab closing means including a lever pivoted to one of said scoops to swing relatively to such scoop, and means including a cam and a follower cooperating therewith, one carried by said supporting means and the other by 90 said lever to modify the swinging movement of said lever thereby to check the opening movement of said scoops.

14. In a grab, the combination of a pair 95 of pivoted scoops, supporting means including a pair of links to which said scoops are pivoted, respectively, and on which said scoops tend to gravitate toward an open position, closing means including a closing lever pivotally connected to one of said scoops intermediate the pivotal connection 100 of such scoop with its associated link and the pivotal axis of said scoop to utilize the weight of said lever to assist in the opening of the grab, and locking means including a pair of jaws carried by said lever and a part receivable therebetween and carried by such scoop normally locking said lever against descent about its pivotal connection with such scoop.

In testimony whereof, I have signed my 110 name to this specification.

ALMON E. NORRIS.
